UNITED STATES PATENT OFFICE.

JAMES W. McNEIL, OF NEWARK, NEW JERSEY.

SHEET-METAL BARREL.

1,417,617.

Specification of Letters Patent. Patented May 30, 1922.

Application filed February 2, 1921. Serial No. 441,812.

To all whom it may concern:

Be it known that I, JAMES W. McNEIL, a subject of the King of Great Britain, and resident of Newark, in the county of Essex 5 and State of New Jersey, have invented certain new and useful Improvements in Sheet-Metal Barrels, of which the following is a specification.

This invention relates to improvements in 10 metal barrels, and has for its objects to provide a strong barrel body formed of a plurality of staves which may be easily and economically manufactured of thin sheet metal, and to provide tight and firmly in- 15 terlocked joints between the staves.

In the drawings:

Fig. 1 is a side elevation of a barrel body showing the preferred embodiment of the invention;

20 Fig. 2 a fragmentary vertical sectional view of the barrel body;

Fig. 3 a perspective view of one of the staves;

25 Fig. 4 a fragmentary perspective view of one of the staves on a larger scale;

Fig. 5 a detail perspective view showing the manner of assembling the staves;

Fig. 6 a section on the line VI—VI of 30 Fig. 5;

Fig. 7 a section on the line VII—VII of Fig. 5; and

Fig. 8 a section on the line VIII—VIII of Fig. 5.

The barrel body is of the usual bilge form 35 and is made up of a plurality of staves, having chine portions 1 at their ends and body portions 2 curved or bowed both longitudinally and transversely of the staves. The body portion of each stave is provided along 40 one side edge with an integral inwardly extending flange 3 of channel form, the mouth of the channel facing outwardly.

The flanges 3 are provided at intervals 45 with slots 4 extending along the base of the channel. The slots 4 extend longitudinally of the flange 3 a sufficient distance to receive substantial locking tongues 5 formed on the flange 6 of the next adjacent stave, each stave being provided at one edge with 50 a flange 3 and at its opposite edge with a flange 6. The tongues 5 on the flange 6 of each stave are located directly opposite the slots 4 in the flange 3 of the stave. The slots 4 are just sufficiently long to receive 55 tongues 5. In the construction shown, the slots are wide transversely of the stave, ex-

tending from a point adjacent the inner edge of the inner web of flange 3 to the outer edge of the outer web of flange 3.

The channels in the doubled flanges 3 are 60 just wide enough to receive flanges 6. In assembling the parts, the flange 6 on each stave is passed inwardly into the channel of the flange 3 on the adjacent stave, the tongues 5 passing through slots 4 as shown 65 in Figs. 5 and 6, and the tongues 5 are then bent laterally and outwardly flat against the outer faces of the inner webs of flanges 3, as shown in Fig. 7.

The chine portions 1 of the staves are bent 70 laterally relatively to the body portions 2 of the staves so as to form cylindrical chines at the ends of the bilged barrel body when the staves are assembled. The flanges 3 and 6 terminate at the inner ends of the chines, 75 and the ends of the flanges form shoulders upon which suitable barrel heads (not shown) may rest. Suitable metallic hoops 7 may be secured around the outer side of the barrel body. The body portions of the 80 staves are preferably provided with longitudinally extending stiffening corrugations as shown at 8.

The construction shown provides a tight 85 joint between each pair of staves, and it will be observed that the joint is so formed that the staves are securely held against relative movement in any direction.

What I claim is:

1. A sheet metal barrel body comprising 90 a plurality of sheet metal staves each of which is provided with a flange of channel form along one edge thereof and a flat flange along the opposite edge thereof, the flat flange on each stave being embraced by 95 the channel flange on the adjacent stave and having tongues along its inner edge extending through slots in the inner edge of the channel flange and bent laterally and outwardly flat against one side of said channel 100 flange.

2. A barrel body comprising a plurality 105 of sheet metal staves provided with integral inwardly extending side flanges one of which is of channel form and the other of which is flat and provided with tongues along its inner edge, the channel flange on each stave embracing the flat flange on an adjacent stave and having slots at the base of the channel therein through which the tongues 110 on the flat flange extend, said tongues being bent laterally and outwardly against the

outer side of the inner web of the channel flange.

3. A barrel body comprising a plurality of sheet metal staves having chine portions and longitudinally corrugated body portions, the body portion of each stave having one edge bent inwardly and then laterally and outwardly to form a channel flange and its opposite edge bent inwardly to form a flat 10 flange, the flat flange on each stave being

embraced by the channel flange on an adjacent stave and provided with tongues along its inner edge, the channel flanges having slots therein through which the tongues extend, and said tongues being bent around one 15 web of the channel flanges.

In testimony whereof I hereunto affix my signature.

JAMES W. McNEIL.
